PRINTING TELEGRAPH APPARATUS

Walter J. Zenner, Des Plaines, Ill., assignor to
Teletype Corporation, Chicago, Ill., a corpora-
tion of Delaware

Application December 31, 1936, Serial No. 118,525

12 Claims. (Cl. 178—33)

This invention relates to printing telegraph apparatus, and particularly to selector mechanisms for controlling the operation of such apparatus.

An object of the invention is the provision of 5 instrumentalities in a selector mechanism for easy, quick, and accurate adjustment of its elements for efficient operation.

Another feature of the invention is to provide a selector mechanism of the assisted armature type 10 in which the armature assisting lever is at all times free to engage the element by which it is operated.

Another object of the invention is to provide a selector mechanism in which the energy developed 15 by the selector magnet is minimized.

A feature of the invention is to provide a universally adjustable mounting for the selector magnet of a selector mechanism.

Another feature of the invention is to provide 20 completely resilient interconnection between the armature assisting lever and the selector lever in a selector mechanism.

The invention contemplates numerous other 25 features capable of incorporation into selector mechanisms in various combinations.

For a full and complete understanding of selector mechanisms of the type to which the several features of the invention may be applicable, reference may be had to Patent No. 1,937,376 30 granted November 28, 1933 to Walter J. Zenner.

Briefly, the invention contemplates, in accordance with one embodiment thereof, a pivotal mounting for the magnet of a selector unit to vary the clearance between the magnet and its 35 armature without altering the relationship between the armature and other elements of the selector mechanism. Such pivotal mounting may be fixed or movable, and if movable, may permit adjustment of the armature with respect to other 40 elements of the selector unit independently of the adjustment of the relationship between the magnet and its armature.

In another of its embodiments, the invention 45 contemplates the armature of a selector magnet may be detached and dissociated from the armature assisting lever, and may instead be applied to a latch which has a shoulder to engage a lug formed on the flutter lever or may be applied directly to a selector lever which is movable under 50 the control of the flutter lever.

For a complete understanding of the invention, reference may be had to the following detailed description, taken in connection with the accompanying drawings in which

55 Fig. 1 is a plan view, partly in section, of a se-

lector mechanism showing magnet adjusting means in accordance with one embodiment of the invention;

Fig. 2 is a sectional view taken on the line 2—2 of Fig. 1;

Fig. 3 is a vertical sectional view taken substantially on the line 3—3 of Fig. 1;

Fig. 4 is a fragmentary plan view showing a modified magnet adjusting system;

Fig. 5 is a vertical sectional view taken substantially on the line 5—5 of Fig. 4;

Fig. 6 is a fragmentary plan view showing another form of magnet adjusting system;

Fig. 7 is a vertical sectional view taken on the line 7—7 of Fig. 6;

Fig. 8 is a plan view showing a selector mechanism in which the selector magnet controls a latch;

Fig. 9 is a vertical sectional view taken on the line 9—9 of Fig. 8;

Fig. 10 is a fragmentary elevational view of the selector mechanism of Fig. 8 as seen from the upper edge thereof;

Fig. 11 is a fragmentary plan view showing a selector mechanism in which periodic movement 25 of the flutter lever is not affected by the operation of the magnet armature; and

Fig. 12 is a vertical sectional view taken on the line 12—12 of Fig. 11.

Referring now to the drawings in which identical reference characters designate corresponding parts throughout the several views, and particularly to Figs. 1 and 2, reference numeral 21 designates a mounting plate for a selector mechanism for printing telegraph apparatus. A selector 30 magnet assembly indicated generally by the reference numeral 22 comprises a bracket 23 to which is secured, by means of screws 24, a magnet core 26. Core 26 has two arms, each of which supports a winding 27 which is adapted to be connected to a telegraph line. At their outer ends the arms of core 26 terminate in pole faces 28.

Bracket 23 supports opposed pivot screws 29, which in turn pivotally support an armature lever indicated generally by the reference numeral 31 45 and comprising arms 32 and 33. Arm 32 has rigidly secured thereto magnet armature 34 which terminates in alignment with pole faces 28. The outer end of arm 33 terminates in cam follower portion 36.

The lower most of pivot screws 29 is supported in a boss 30 which is integral with bracket 23 and extends through a closely fitting aperture in mounting plate 21 to serve as a pivotal mounting for the bracket. The bracket is provided at a 50 55

- point spaced from pivotal mounting screw 29 with an open slot 31, having parallel sides, and in which is disposed head 33 of an adjusting screw which has the shank 39 eccentric with respect to head 38. Bracket 23 is provided with a plurality of clearance holes 41 which may be arcuate on radii originating on the axis of boss 30, and in which are disposed clamping screws 42 threadedly engaging mounting plate 21.
- 10 Cam follower portion 36 of armature lever 31 is disposed in operative alignment with an armature cam 43 included in a selector cam assembly, indicated generally by the reference numeral 44, mounted on power driven shaft 46 extending through mounting plate 21. Cam assembly 44 is arranged to be driven from shaft 46 through discs 47 fixed to shaft 46, resilient discs 48 in frictional engagement with discs 47 and discs 49 fixed to cam assembly 44 and in frictional engagement with discs 48. Discs 47, 48, and 49 constitute friction clutch assemblies. Selector cam assembly 44 includes a stop arm 51 which is arranged to be arrested and released for rotation alternatively under the control of a stop gate 52 included in a stop gate assembly 50. Stop gate assembly 50 has as its foundation a plate 53 which is pivoted below a plate 55 by means of pivot screws 54 carried by plate 55 which is supported by posts 56 mounted on mounting plate 21.
- 20 An arm 57 mounted on pivot screw 54 above plate 55 has extending therethrough the shank of a knurled-headed screw 58 which threadedly engages stop gate mounting plate 53. Plate 53 may be adjusted pivotally about pivot screw 54 and may be clamped in any desired position of adjustment by drawing plate 53 and arm 57 into clamping engagement with plate 55 by means of screw 58.
- Stop gate 52 is pivotally mounted on stud 59 carried by plate 53, and is biased clockwise by a tension spring 60. The stop gate has a portion disposed in the path of stop arm 51, when in extreme clockwise position, and it may be latched in that position by shouldered latch lever 61.
- 40 Lever 61 is pivotally mounted on the under side of plate 53 and is urged by spring 62 into latching engagement with stop gate 52. Latch lever 61 is rocked against the resistance of compression spring 62 to lift its shoulder out of latching engagement with the stop gate by a plunger pin 63 in the operating path of which is disposed one arm of a bell crank 64, the other arm of which engages latch lever 61. A plunger operating screw 65 carried by extension 35 of armature lever arm 33 in alignment with plunger pin 63 shifts the pin to effect the release of the stop gate when the armature lever is in its extreme clockwise position, at which time armature 34 is out of engagement with pole face 28. Plunger pin 63 is retracted by spring 62 and permits latching lever 61 to latch stop gate 52 when armature lever 31 is in its extreme counterclockwise position, at which time armature 34 engages pole face 28.
- 50 A selector lever assembly, generally indicated by the reference numeral 66, is supported by mounting plate 21 and comprises a mounting bracket 67 secured to mounting plate 21 by screws 68, and a selector lever 69 pivotally supported by bracket 67 by means of pivot screws 71. A tension spring 72 has one end connected to selector lever 69 and the other end secured to extension 35 of armature lever arm 33. Said extension also carries an abutment screw 73 which is adjustable with respect thereto, and the head

of which abuts selector lever 69 intermediate its ends. At its free end, which is the right-hand end as viewed in Fig. 1, selector lever 69 is provided with spaced depending arms 74, by means of which the setting of selector elements of a sword and T-lever selector assembly is controlled.

The sword and T-lever assembly is designated generally by the reference numeral 76, and comprises a plurality of thin, flat selector fingers, or sword levers 77, and an equal number of T-levers 78 individually aligned with the sword levers 77. Sword levers 77 are individually supported by spacer plates 79 which also separate the T-levers 78 and which are mounted on studs 81, and are spaced apart by washers 82. Each of the sword levers 77 has at its left-hand end, as viewed in Fig. 1, a disc-like portion 83 which is fitted into a correspondingly shaped aperture in a sword operating bell crank lever 84 pivotally mounted on pivot pin 86. Each of the bell crank levers 84 is arranged to be rocked counterclockwise by one of a plurality of cam projections 87 carried by the cam assembly 44 in helical arrangement. Adjacent to the disc-like portion 83 each sword lever 77 is provided with oppositely extending arms 88 which terminate in abutments 89.

T-levers 78 are rotatably mounted upon pivot pin 91 carried by mounting plate 21 and each of the levers 78 is provided with an arm 92 which terminates in a disc-like portion 93. T-levers 78 are intended to be articulated, by means of the disc-like portions 93, to code bars, code discs, or other permutation code elements (not shown) as disclosed in Patent 1,745,633 granted February 4, 1930, to S. Morton et al.

Pivot pin 86, in addition to supporting sword lever operating bell cranks 84, also pivotally supports a locking bell crank lever 96 which has one arm 97 terminating in a cam follower portion 98 which engages a locking cam 99, included in cam assembly 44, and has another arm 99 terminating in a locking blade 101 adjacent to which selector 69 is provided with a locking lug 102.

Selector lever 69 is adapted to be rocked, in a manner which will be described later, through an arc sufficient to bring one or the other of its arms 74 into the path of one or the other of abutments 89 of sword levers 87 as the sword levers are reciprocated leftwardly by associated bell cranks 84, and such angular movement of selector lever 69 is sufficient to bring locking lug 102 from one side to the other of locking blade 101. Continued reciprocation of a sword lever, after one of its abutments 89 has engaged one of the depending arms 74 of selector lever 69, causes the sword lever to move angularly about the center of its disc-like portion to bring its free end into engagement with its associated T-levers 78 at either side of the pivotal mounting 91 thereof. The angular movement of sword levers 78 is limited by stop pins 103 carried by mounting plate 21. Tension springs 106 and 107 bias armature lever 31 and sword lever bell cranks 84 respectively in clockwise direction, and tension spring 108 biases locking bell crank lever counterclockwise.

The selector mechanism shown in Figs. 1 and 2 is adapted to be controlled by permutation code signals comprising marking and spacing impulses in various combinations received by the selector magnet winding 27 from the telegraph line to which it is connected. When the selector mechanism is not operating and is responding to a stop impulse, armature 34 is attracted to pole face 28, and abutment screw 65 is drawn away

from plunger pin 63, which, being retracted, causes stop gate 52 to be latched to hold cam assembly 44 motionless. When a code signal combination is received, the first impulse thereof is the start impulse which results in deenergization of the selector magnet and permits spring 106 to rotate armature lever 31 clockwise, thus drawing armature 34 away from pole face 28 and depressing plunger pin 63, whereby stop gate 52 is released from latch lever 61. Cam assembly 44 rotates through one revolution during the reception of a code combination, and, in rotating, cam 43 rocks armature lever 31 counterclockwise, cam 98 unlocks selector lever 69, these operations occurring periodically, and cam projections 87 rock sword lever bell cranks 84 counterclockwise. All of these operations occur in timed relation to the reception of code signal impulses. If the selector magnet is energized at the instant armature cam 43 actuates armature lever 31 to bring armature 34 into engagement with pole face 28, the armature will be held and armature lever 31 will be held in its extreme counterclockwise position, whereby abutment screw 73 will be drawn away from selector lever 69. Upon the unlocking of selector lever 69, tension spring 72 will cause the lever to be rotated to its extreme counterclockwise position, whereby one of the arms 14 will be presented to an abutment 89 of a particular sword lever 77 in accordance with the energized condition of the selector magnet. When the selector magnet is deenergized at a time that armature 34 is brought into engagement with pole face 28 by armature cam 43, the armature will not be held, and the selector lever, when unlocked, will be positioned in accordance with the deenergized condition of the selector magnet.

40 A code signal combination concludes with a stop impulse which is represented by the energized condition of the selector magnet. The armature is thus held, and armature lever 31 is retained in its extreme counterclockwise position, whereby plunger pin 63 is permitted to be 45 retracted, and stop gate 52 locked. It follows from this that cam assembly 44 is arrested at the conclusion of one revolution and awaits release by the start impulse of the next code signal combination.

50 The feature of the invention disclosed in Figs. 1 and 2 is the arrangement for adjusting the selector magnet represented by boss thirty, slot 37, eccentric screw head 38, and arcuate clamping screw holes 41. With screws 42 loosened, bracket 55 23 may be rotated through a small angle about the axis of boss 30 by rotating eccentric screw head 38. The result of such adjustment is to vary the clearance between selector magnet pole face 28 and armature 34. The relationship between armature lever arm 33 and armature cam 43 is not altered by such adjustment of the magnet armature clearance because of the fact that the armature lever 31 is pivoted upon the same axis as is bracket 23. Thus the adjustment afforded by the slot 37 and eccentric screw head 38 is confined to the desired point, and no other portion of the selector mechanism is affected.

Figs. 4 and 5 disclose a somewhat different arrangement for varying the space between a selector magnet armature and its pole face. Certain portions of the apparatus shown in Figs. 4 and 5 are identical with portions of the apparatus shown in Figs. 1 and 2, and are identified by the same reference numerals.

75 Figs. 4 and 5 are fragmentary views and dis-

close only those portions of a selector mechanism which need be shown to indicate the modified arrangement. Except for the modification, the selector mechanism having cooperation with the elements shown in Figs. 4 and 5 may be identical with the mechanisms shown in Figs. 1 and 2. Referring specifically to Figs. 4 and 5, reference numeral 21 identifies selector mounting plate as in Figs. 1 and 2. Mounting plate 21 supports a selector magnet assembly, identified generally by the reference numeral 111, and comprising a bracket 112 to which magnet core 113 is secured by means of screws 114. Core 113 has two arms, each of which supports a helical winding 116 and terminates in a pole face 115. Bracket 112 pivotally supports armature lever 31 by means of pivot screws 117 similarly to the manner in which bracket 23 (Fig. 1) supports armature lever 31. The lower pivot screw 117 does not extend through the mounting plate 21, and bracket 112 is not pivotally mounted on the axis of rotation of armature lever 31 as is bracket 23 in Fig. 1. Bracket 112 is pivoted to plate 21 by means of pivot screw 118, which passes through an aperture in bracket 112 at a point remote from the pivot screws 117 and substantially on a line passing through the cam follower portion 36 of flutter lever 31 and the axis of pivot screws 117.

Adjacent to the lower pivot screws 117, casting 112 is provided with an open slot 119 in which is disposed a head 121 of an adjusting screw, the shank 122 of which is eccentric to the head 121 and passes through mounting plate 21. All other parts of the selector mechanism 35 may be identical with corresponding elements shown in Fig. 1, and certain of these elements, such as selector lever assembly 66 and armature lever assembly 31, are specifically identified by reference characters. 40

In the structure shown in Fig. 4, rotation of eccentric screw head 121 causes selector magnet bracket 112 to move through a small angle about screw 118 as a pivot so that the axis of rotation of armature lever 31 shifts through an arc which crosses the line defined by cam follower terminal portion 36 of arm 33 of armature lever 31 and pivot screw 118. The space between armature 34 and pole face 115 may thus be varied, and in the making of such adjustment the relationship between armature lever 31 and the armature cam is not materially altered, due to the fact that the rocking of armature lever 31 about its point of engagement with the armature cam, as the position of bracket 112 is adjusted, is only very slight. 45 50 55

Attention is now directed to Figs. 6 and 7, in which is shown a modification of the structure of Fig. 1, by means of which the relationship between the armature lever and the armature cam may be varied without interfering with a predetermined, previously established adjustment of the armature with respect to its pole face. It will be noted that the selector magnet assembly 22 is identical with that shown in Fig. 1 with the single exception that the clearance holes now designated by the reference numeral 126, through which the clamping screws 42 extend, are not arcuate to provide rotational movement only of selector magnet bracket 23, but are instead of sufficient size to permit the bracket to be moved in all directions. The boss for defining rotation of the magnet bracket, identified in this figure by reference numeral 127, is not retained in mounting plate 21, as in Fig. 2, but

extends through a clearance hole 128 in plate 21 and engages an arm 129 positioned below mounting plate 21 and pivoted to the mounting plate by means of pivot screw 131. At its opposite end 5 the arm 129 terminates below a circular aperture 130 in mounting plate 21, and has formed in the end thereof an open recess 132. Arm 129 may be moved angularly about its pivotal mounting 131 by inserting into the circular aperture above 10 recess 132 an implement 133 having a cylindrical portion dimensioned to enter and be rotationally guided within aperture 130, and having an eccentric projection 134 which enters recess 132 in arm 129. By rotating the implement, angular 15 movement is imparted to arm 129, which causes the pivotal mounting 127 of magnet bracket 23 and armature lever 31 to move in an arc, the radius of which is the distance from the axis of boss 127 to that of screw 131. Cam follower 20 portion 36 of armature lever 31 is thus shifted with respect to the armature cam by movement of the entire bracket 23, but the spacing of armature 34, with respect to its pole face 28, is maintained unchanged due to the fact that the bracket 25 23 is guided in its movement by eccentric screw head 38 disposed in the parallel-sided slot 37.

Figs. 8 and 9 illustrate a modification of the selector mechanism shown in Figs. 1 and 2, in which the selector magnet armature, instead of 30 being rigidly connected to the armature assisting lever, is connected to a latch which cooperates with the armature assisting lever to hold it in position corresponding to a selective condition, which is represented by the energized condition of 35 the selector magnet. It may be noted, in connection with the structure shown in Fig. 1, that the position of the armature lever 31 determines the position of selector lever 69 when that lever is unlocked, and that the tension spring 106 must be 40 of sufficient strength to move armature lever 31 and selector lever 69 to their extreme clockwise positions when the armature 34 is not attracted by the selector magnet, and the armature lever is not moved out of its extreme clockwise position 45 by the armature cam. When armature 34 is to be held by the magnetic attraction of core 26, the attractive force must be greater than the tension of spring 106, and the energizing current must be of sufficient magnitude to provide the necessary attraction. In the structure shown in Figs. 8 and 9, the armature assisting lever spring may be considerably lighter than the one required in the selector mechanism shown in Figs. 1 and 2 because the selector magnet is not required to overcome 50 the tension of that spring. As indicated in Figs. 8 and 9, selector magnet assembly 22, sword and T-lever assembly 76, and adjustable stop gate assembly 50, identical with corresponding assemblies previously designated in connection with 55 Fig. 1, are mounted on mounting plate 136. Also, power-driven shaft 46 extends through an aperture in mounting plate 136 and supports selector cam assembly 44 arranged to be frictionally driven thereby. Selector lever 69 is pivotally mounted 60 on a bracket 137 of which no details of construction are shown, but which may, if desired, take the form of an adjustable bracket such as that disclosed in copending application of E. W. F. Hanke, Serial No. 116,271 filed December 17, 1936. 65 Cam-operated locking bell crank 96 is pivotally mounted upon pivot pin 86, as are also sword lever operating bell cranks 84. Bracket 23 of the selector magnet assembly has opposed pivot screws 138 which pivotally support a bell crank lever 139, 70 one arm of which carries selector magnet arma-

ture 141, and the other arm of which terminates in a latching shoulder 142. Armature assisting lever 143 is mounted for pivotal movement by pivot screws 144 on a bracket 140 which may be similar to bracket 137. Armature assisting lever 143 has a portion abutting yieldable spring member 145 carried by armature 141. A lug 146 is adapted to be engaged by shoulder 142 of bell crank 139, and the lever 143 also has a cam follower portion 147. Tension spring 148 biases 10 armature assisting lever 143 in clockwise direction. Tension spring 72 and abutment screw 73 constitute interconnection between armature assisting lever 143 and selector lever 69, as in the structure shown in Fig. 1. A light tension spring 150 biases 15 bell crank lever 139 in counterclockwise direction, whereby it tends to be withdrawn from latching engagement with lug 146 of selector lever 143, and armature 141 tends to be retracted from its pole face. 20

In operation, armature assisting lever 143 is periodically rocked counterclockwise by armature cam 43, whereby the lever engages yieldable spring member 145 and forces armature 141 into engagement with its pole face, and latch shoulder 142 25 into latching engagement with lug 146. If armature 141 is not then held due to energized condition of the selector magnet, spring 148 disables latching bell crank 139, and armature assisting lever 143 returns to its extreme clockwise position 30 before selector lever 69 is unlocked by bell crank 96 actuated by cam 98. If, however, the selector magnet is energized and holds its armature 141, armature assisting lever 143 will be latched up 35 and prevented from immediately returning to its extreme clockwise position, and when the selector lever 69 is unlocked by its locking bell crank 96, it will be drawn to its extreme counterclockwise position by spring 72 to effect a setting of one of the sword levers 77 in accordance with the energized 40 condition of selector magnet winding 27. Winding 27 is required to carry only sufficient energizing current to cause armature 141 to be held in opposition to tension spring 150. None of the 45 stored energy of armature assisting lever restoration spring 148 is operative upon armature 141, but is instead resisted by latching shoulder 142 which has positive blocking relation to latching lug 146 until the selector magnet releases its armature. With the arrangement shown in Figs. 50 8 and 9 a much lower current value may be employed for operating the selector magnet than in the arrangement shown in previously described Fig. 1.

In Figs. 8 and 10 there is shown an arrangement 55 for varying the air gap between the selector magnet pole faces 28 and armature 141 which is related to but differs from the arrangement shown in Figs. 1 and 2, and which constitutes the preferred construction. It will be noted, by reference to Fig. 9, that magnet bracket 23 has a depending boss 160 which, in addition to mounting the lower pivot screw 138 for the latching bell crank 139, also establishes a center of rotation for selector magnet bracket 23, in the same manner 60 that boss 30 (Fig. 1) constitutes a pivot for the selector magnet bracket shown in Fig. 1. The selector magnet bracket 23 (Fig. 8) is provided with arcuate apertures 41, the arcs of which have their centers on the axis of pivot screw 138, and 65 through which extend clamping screws 42 to threadedly engage mounting plate 136. At a point remote from pivot screw 138, and corresponding to the location of open, parallel-sided slot 37 (Fig. 1) bracket 23 (Figs. 8 and 10) threadedly supports 70

75

the shank of an adjusting screw 149 which is provided with head 166, and spaced therefrom along the shank, flange 167. A stud 168 is rigidly secured to mounting plate 136, and extends upwardly into the space between head 166 and flange 167. Screw head 166 may be provided with the usual slot (not shown) for cooperation with a screw driver, and there may be provided in the periphery of the head, sockets 169 into which a pin may be inserted for rotation of screw 149 in the manner in which capstans are rotated. The sockets 169 permit rotation of screw 149 by suitable implement when the installation of the selector mechanism is such as to prevent access to the slotted head by a screw driver.

It will be apparent that when screw 149 is rotated, it can undergo no axial movement, due to the confining action of head 166 and flange 167 upon stud 168. Since screw 149 threadedly engages bracket 23, the latter must move toward or away from stud 168 as the screw is rotated, and in so moving it pivots about screw 138 and varies the air gap between pole faces 28 and armature 141.

Although there is no specific showing in the drawings, attention is directed to the fact that the magnet adjustment afforded by screw 149 and stud 168 may be substituted for the air gap adjusting system comprising slot 37 and screw 38 in the embodiment of the invention shown in Figs. 6 and 7. In that embodiment, the magnet bracket 23 is arranged to undergo rectilinear movement as well as pivotal movement, as previously described, and the open slot 37 permits the rectilinear movement. Should screw 149 and stud 168 be substituted for screw 38 and slot 37 in Fig. 6, bracket 23 would be as free to move rectilinearly as in the present showing, and during such movement, the shank of screw 149 would be shifted with respect to stud 168 in the direction of movement of bracket 23 rectilinearly, there being no opposition exerted by stud 168 to movement of screw 149 rectilinearly.

Another modification of the invention, in which a still different relationship between armature assisting lever, selector lever, and magnet armature exists, is shown in Fig. 11. Referring now to that figure, it will be noted that a selector mounting plate 151 supports a selector magnet assembly 22 and brackets 164 and 152 on which selector lever 153 and armature assisting lever 156 are respectively pivotally mounted by means of pivot screws 154 and 157 respectively. The brackets 152 and 164 may be similar to brackets 135 and 140, and may be adjustable in the same manner that they may be made adjustable. The bracket 164 which mounts the armature supporting lever may, if desired, be a part of the magnet bracket in the same manner that armature supporting levers 31 and 139 shown in Figs. 1 or 4 and 8 respectively are mounted on portions of the selector magnet bracket. Armature assisting lever 156 is urged into extreme clockwise position by tensioning spring 155 and is periodically rocked counterclockwise by armature cam 43 included in selector cam assembly 44 carried by power-driven shaft 46. The armature of the selector magnet is designated 158 and is mounted directly on selector lever 153, which has, at its free end, locking lug 102 similar to that employed on selector lever 69 (Fig. 1) with which there cooperates locking bell crank lever 96. Since selector lever 153 carries the selector magnet armature 158, the tripping of the stop gate for the selector cam assembly 44 in re-

sponse to a start impulse must be under the control of that lever. Accordingly, lever 153 is provided with an arm 171 having abutment screw 172 in operative alignment with stop gate latch tripping plunger pin 63 of adjustable stop gate assembly 5.

The interconnection between selector lever 153 and armature assisting lever 156 is shown in detail in Fig. 12 by reference to which it will be observed that selector lever 153 is provided with spaced depending arms 159 in alignment with which are depending arms 161 of armature assisting lever 156 spaced apart a greater distance than are the arms 159. The arms 159 of armature assisting lever 153 are apertured to receive shou- 15 dered pins 162, which are urged in opposite directions by compression spring 163 to force their shoulders into abutting relation with the inner surfaces of arms 159. With the arrangement shown in Fig. 9, selector lever 153 tends to be centered with respect to armature assisting lever 156, and if the latter is moved angularly, an unbalance is created in the combination of pins 162 and spring 163 which causes the selector lever 153 to be moved in a direction to eliminate the unbalance when it is unlocked by locking bell crank 96. It will be observed that the interconnection between armature assisting lever 156 and selector lever 153 is resilient or permissive in both directions, as contrasted with interconnections previously described, comprising a tension spring and an abutment screw, the combination of which affords a permissive or resilient interconnection in one direction, and a positive interconnection in the other direction.

In the operation of a selector mechanism, as disclosed in Fig. 11, it will be presumed that the energizing current of the selector magnet is sufficient to hold selector lever 153 in opposition to a condition of unbalance in the spring interconnection between selector lever and the flutter lever, but is insufficient to attract the selector lever from its extreme clockwise to extreme counterclockwise position. Due to the periodic rocking of armature assisting lever 156 counterclockwise by cam 43, an unbalance, tending to rotate selector lever 153 counterclockwise, will be established in the interconnecting pins 162 and spring 163, and when locking bell crank 96 is actuated by cam 98 to unlock selector lever 153, the latter will be rotated to bring armature 158 into engagement with the pole face of the selector magnet. If that magnet is then energized, the selector lever 153 will be held in its extreme counterclockwise position after the armature assisting lever has returned to its extreme clockwise position due to escapement of its cam follower portion from an apex of flutter cam 43, and a selective condition corresponding to a marking signal is thus established, whereupon locking bell crank cam 98 permits locking bell crank 96 to lock lever 153.

If instead of being energized at the time the armature assisting lever 156 is rotated counterclockwise, selector magnet should be deenergized, in response to a spacing signal, the selector lever 153 will not be held and will return to its extreme clockwise position when the armature assisting lever returns to its extreme clockwise position, whereupon the selector lever may be locked in that position, which corresponds to a spacing signal condition of the selector magnet.

With the arrangement shown in Figs. 11 and 12, the selector magnet armature is not associated with the armature assisting lever, as in the

previously described structures, but is associated with the selector lever. The selector magnet is not called upon to actuate selector lever 153, but is only required to hold it in opposition to a relatively weak unbalance in the centering spring mechanism when the armature lever returns to its extreme clockwise position. The restoring spring for the armature assisting lever may thus be as heavy as desired. Furthermore, the armature assisting lever is never held out of engagement with the armature cam, as it may be in the structure shown in Fig. 1, by armature 28 and in Fig. 6 by latch lever 139, but is instead continuously responsive in its movements to the contour of the armature cam.

What is claimed is:

1. In a selector mechanism, an electromagnet, a pivotal mounting therefor, a rotatable cam, a lever pivoted coaxially with the pivotal mounting of said electromagnet and having a portion engageable with said cam, an armature for said electromagnet carried by said lever, and means for pivotally moving said electromagnet to vary its relation with respect to said armature independently of a predetermined relationship between said lever and said cam.

2. In a selector mechanism, a mounting plate, a bracket pivotally supported thereby, an electromagnet carried by said bracket, a lever pivotally supported by said bracket coaxially with the pivotal mounting of said bracket, a cam carried by a rotatable shaft, said lever having a portion engageable with said cam as a follower, an armature carried by said lever for cooperation with said electromagnet, and means for pivotally moving said bracket to vary the spacing between said electromagnet and the armature carried by said lever independently of the predetermined relationship between said lever and said cam.

3. In a selector mechanism, an electromagnet, a pivotal mounting therefor, a rotatable cam, a lever pivoted at a point remote from the pivotal mounting of said electromagnet and having a portion engageable with said cam, an armature for said electromagnet carried by said lever, and means for pivotally moving said electromagnet to vary its relation with respect to said armature independently of a predetermined relationship between said lever and said cam.

4. In a selector mechanism, an electromagnet, a pivotal mounting therefor, rotatable cam, a lever pivoted at a point remote from the pivotal mounting of said electromagnet and having a portion engageable with said cam, an armature for said electromagnet carried by said lever, and means for shifting the pivotal mounting for said lever to vary the relationship between said armature and said electromagnet substantially independently of a predetermined relationship between said lever and said cam.

5. In a selector mechanism, a mounting plate, a bracket, an electromagnet carried by said bracket, a pivotal interconnection between said mounting plate and said bracket adjacent one end of said electromagnet, a lever pivotally supported by said bracket adjacent the other end of said electromagnet, a cam carried by a rotatable shaft, said lever supporting an armature for the electromagnet and having a portion engaging said cam as a follower, and means adjacent to the point of pivotal movement of said lever for shifting said point in an arc intersecting a straight line between the pivotal interconnection of said bracket with said mounting plate and the point of engagement of the lever with the

cam for varying the gap between the electromagnet and the armature.

6. In a selector mechanism, an electromagnet, a pivotal mounting therefor, a rotatable cam, a lever pivoted coaxially with the pivotal mounting of said electromagnet and having a portion engageable with said cam, an armature for said electromagnet carried by said lever, and means for shifting the coaxial pivotal mountings for the electromagnet and the lever to vary the relationship between the lever and the cam independently of a predetermined relationship between the electromagnet and its armature.

7. In a selector mechanism, a mounting plate, a lever arm pivotally mounted on said plate, a bracket carried by said plate and pivotally connected to said arm, a lever pivotally supported by said bracket coaxially with the pivotal connection of said bracket to said arm, an electromagnet carried by said bracket, a power driven cam, said lever supporting an armature and having a portion engageable with said cam, means for varying the relationship between said electromagnet and said armature and means for varying the relationship between said cam and said lever, the effectiveness of said means being mutually independent.

8. In cooperation with a selector mechanism including a mounting plate having a plurality of apertures, an arm pivoted to said plate on the under side thereof, and having a slot therein in registry with one of said apertures of lesser width than the diameter of said apertures, and an assembly of selection performing elements having a portion extending through another of said apertures and pivotally connected to said arm, an implement for effecting pivotal movement of said arm including a cylindrical shank dimensioned to enter and be rotationally guided by the aperture with which the slot in said arm registers and an eccentrically disposed projection of said shank dimensioned to enter the slot in said arm.

9. In an electromechanical device, a bracket, a pivotal mounting for said bracket, an electromagnet supported by said bracket, a power driven cam, a lever pivotally supported by said bracket and having a portion engageable with said cam, an armature carried by said lever for cooperation with said electromagnet, and means for shifting said bracket about its pivotal mounting to vary the spacing between said electromagnet and said armature substantially independently of a predetermined relationship between said lever and said cam.

10. In an electromechanical device, a mounting plate, a pivotally mounted bracket carried by said plate, an electromagnet supported by said bracket, a power driven shaft extending through said plate, a cam carried by said shaft, a lever pivotally supported by said bracket and having a portion engageable with said cam, an armature for said electromagnet carried by said lever, and means cooperating with said mounting plate in said bracket for shifting said bracket about the pivotal mounting for varying the spacing between said electromagnet and said armature substantially independently of a predetermined relationship between said lever and said cam.

11. In a selector mechanism, a mounting plate, a pivotally mounted bracket supported by said plate and having a slot therein, an electromagnet secured to said bracket, a rotatable cam, a selection controlling lever pivotally supported by said bracket and having a portion engageable with said cam, an armature for said electromagnet

carried by said lever, and a rotatable member supported by said mounting plate and having an eccentric head disposed in said slot in the bracket for pivoting said bracket for varying the spacing 5 between said electromagnet and said armature substantially independently of a predetermined relationship between said lever and said cam.

12. In combination a mounting plate, an electromagnet carried by said plate, means for pivoting connecting said electromagnet to said plate, 10 a rotatable cam, a pivotally mounted armature

for said electromagnet controlled jointly by said electromagnet and said cam, and means co-operating with said mounting plate and said electromagnet for imparting pivotal movement to said electromagnet about said pivotal connecting 5 means for varying the spacing between said electromagnet and said armature substantially independently of a predetermined relation between said armature and said cam.
